UNITED STATES PATENT OFFICE

JOACHIM B. SCHARE, OF CHICAGO, ILLINOIS

DESIGN FOR A COMBINED SMOKER'S AND READER'S STAND

Application filed December 7, 1929. Serial No. 33,684. Term of patent $3\frac{1}{2}$ years.

To all whom it may concern:

Be it known that I, JOACHIM B. SCHARE, a citizen of the United States, residing at Chicago, in the county of Cook and State of Illinois, have invented a new, original, and ornamental Design for a Combined Smoker's and Reader's Stand, of which the following is a specification, reference being had to the accompanying drawing, forming part thereof.

The figure on the drawing is a view in perspective of said stand.

I claim:

The ornamental design for a combined smoker's and reader's stand substantially as shown.

JOACHIM B. SCHARE.
